UNITED STATES PATENT OFFICE.

FRANK C. GREEN, OF PITTSFIELD, MASSACHUSETTS, ASSIGNOR TO GENERAL ELECTRIC COMPANY, A CORPORATION OF NEW YORK.

MEANS FOR PREVENTING CONDENSATION OF MOISTURE IN TRANSFORMER-TANKS.

1,108,746.

Specification of Letters Patent.

Patented Aug. 25, 1914.

Application filed November 12, 1913. Serial No. 800,540.

To all whom it may concern:

Be it known that I, FRANK C. GREEN, a citizen of the United States, residing at Pittsfield, county of Berkshire, State of Massachusetts, have invented certain new and useful Improvements in Means for Preventing Condensation of Moisture in Transformer-Tanks, of which the following is a specification.

10 Normally the fluid in which a power transformer is submerged does not quite fill the containing tank and an air space is left above the fluid. The heating of the transformer as it assumes its load or as its load increases, tends to expand the insulating fluid and the air above it, and conversely both tend to contract as they lose their heat as the load decreases. The simplest way to take care of this expansion and 15 contraction is to permit an exchange of air between the inside of the tank and the atmosphere but this results, on each contraction, in an introduction into the tank of some moisture in suspension in the atmosphere, a part of which may condense within the tank and enter the insulating fluid. As is well known the insulating qualities of the oils in which power transformers are usually submerged are greatly affected by 20 the presence of even a very small percentage of moisture. Attempts have been made to prevent this introduction of moisture by providing air drying means in the open connection between the interior of the tank and the atmosphere, but such driers are not entirely satisfactory and do not entirely perform their functions, principally on account of lack of attention by the attendants. Now, I propose to prevent the condensation within 25 the tank of any moisture which may enter. The usual air drier may or may not be used. I do this by providing a heating unit within the air space above the insulating fluid so proportioned that the temperature of the air within this space and, if necessary, of the surrounding materials, is maintained at such a point as to render the condensation of moisture impossible.

In the accompanying drawing which 30 forms a part of this specification, the single figure is an elevation partly in section of a transformer and case provided with my invention.

The transformer tank 1 is of the usual construction. It is provided with the cover 2. Within the tank is the insulating fluid 3 in which is submerged the transformer 4. Through the cover 2 passes the breather 5 for allowing the interchange of air between the interior of the tank and the atmosphere as the temperature changes.

On the under side of the cover 2 is suspended an electrical heating unit 6, the terminals 7 of which are carried out of the tank through the breather 5, this breather 5 forming a convenient passageway for these terminals. The heating unit 6 may be of any desired construction and its exact construction forms no part of this invention. I consider it preferable to locate this heating unit above the surface of the insulating fluid 3.

The heating unit 6 may receive energy at all times while the fluid 3 is within the tank. It may frequently be sufficient, however, for this heating unit to be in service only while the transformer 4 is carrying a low degree of load or is entirely out of service, for generally the heat developed in the transformer itself will be sufficient to maintain the temperature of the air and the surrounding materials at such a degree as to prevent the condensation of moisture.

What I claim as new and desire to secure by Letters Patent of the United States, is:—

1. The combination with a transformer tank, an insulating fluid partly filling said tank, the space above the fluid communicating with the atmosphere, and a transformer submerged in said fluid, of an electric heating device in the space between the surface of the fluid and the top of the tank.

2. The combination with a transformer tank, an insulating fluid partly filling said tank, the space above the fluid communicating with the atmosphere, and a transformer submerged in said fluid, of an electric heating device attached to the cover of the tank above the surface of the insulating fluid.

In witness whereof, I have hereunto set my hand this 5th day of November, 1913.

FRANK C. GREEN.
